UNITED STATES PATENT OFFICE.

MARY K. MUNSON, OF CHICAGO, ILLINOIS.

DESIGN FOR A SPOON.

SPECIFICATION forming part of Design No. 20,979, dated August 11, 1891.

Application filed May 18, 1891. Serial No. 393,209. Term of patent 7 years.

To all whom it may concern:

Be it known that I, MARY K. MUNSON, a citizen of the United States, residing at Chicago, in the county of Cook and State of Illinois, have invented and produced a new and original Design for Spoons, of which the following is a specification, reference being had to the accompanying drawings, which are made a part hereof, and in which—

10 Figures 1 and 2 are plan views of the front and back, respectively, of a spoon embodying the new design.

The bowl A is so outlined and wrought with longitudinal lines a as to represent the bulb 15 of a plant, such as, say, the onion. At its extremity is a protuberance a' , upon which a number of fine roots a^2 are wrought. Upon the handle B a number of equitant leaves C C', &c., are wrought, two of which leaves ex-

tend only a short distance from the bowl, 20 while two others follow the contour of the handle and extend nearly to its extremity. The leaf C is folded upon itself, as at c, and between the two leaves C and C', which spread apart slightly, is wrought a spray of 25 flowers D.

This design may be wrought upon the front of the spoon, as shown by Fig. 1, or upon the back of the spoon, as shown by Fig. 2, or upon both front and back. 30

What I claim is—

The design for spoons, substantially as herein shown and described.

MARY K. MUNSON.
